COMBINED BUMPER AND GRILLE

Donald D. Hoagg, Birmingham, and Bernard N. Smith, Oak Park, Mich., assignors to General Motors Corporation, Detroit, Mich., a corporation of Delaware

Application December 22, 1955, Serial No. 39,436

Term of patent 7 years

(Cl. D14—6)

We claim:

The ornamental design for a combined bumper and grille substantially as shown.
